CLAIM

The ornamental design for a carton substantially as shown and described.

DESCRIPTION

FIG. 1 is a top front perspective view of a carton, showing our new design;

FIG. 2 is a front view of the carton of FIG. 1;

FIG. 3 is a top rear perspective view of the carton of FIG. 1; and,

FIG. 4 is a rear view of the carton of FIG. 1.

The broken lines shown are for the purpose of illustrating parts of the carton forming no part of the claimed design.

1 Claim, 4 Drawing Sheets
